UNITED STATES PATENT OFFICE.

ROBERT ABBOTT HADFIELD, OF WESTMINSTER, AND ALEXANDER GEORGE MCKENZIE JACK AND AUGUSTUS BASIL HOLT CLERKE, OF SHEFFIELD, ENGLAND.

CAPPED ARMOR-PIERCING PROJECTILE.

1,407,532.

Specification of Letters Patent. Patented Feb. 21, 1922.

Application filed November 28, 1919. Serial No. 341,024.

To all whom it may concern:

Be it known that we, Sir ROBERT ABBOTT HADFIELD, ALEXANDER GEORGE MCKENZIE JACK, and AUGUSTUS BASIL HOLT CLERKE, subjects of the King of Great Britain and Ireland, residing, respectively, at Westminster, England, and Sheffield, in the county of York, England, have invented Improvements in or Relating to Capped Armor-Piercing Projectiles, of which the following is a specification.

This invention has for its object to provide a capped armor piercing projectile having a hollow fore-cap which shall combine a percentage weight and distribution of cap material suitable for the attack of thick armor at considerable angles of obliquity with such external contour as is required to obtain a ballistic flight equivalent to that obtained by the use of an ogival form of seven calibres or greater and without exceeding the limits of length of the whole projectile imposed by the consideration of easy stowage and handling.

In forming the outline dimensions of the caps of such armor piercing projectiles it has hitherto been the custom to construct such a cap, in the main, of portions of two arcs of the desired radius struck from centres lying in the transverse plane of the bourelet or within a short distance seldom exceeding say one sixth of the calibre, in rear of the same. At the same time, in order to limit the overall length of the projectile to that convenient for easy handling and stowage, it has been customary to employ a shorter radius than that which would be required to form a true ogive; that is to say, the arcs with which the outline is mainly constructed would cut the plane of the bourelet within the wall of the projectile itself.

While thus producing an outline of a capped projectile of suitable length as mentioned above, this form of construction has the effect of limiting the weight of the cap and imposing a distribution of cap material unsuitable for the successful penetration of thick armor at considerable angles of obliquity. The maximum diameter of a cap so constructed is further considerably less than the calibre of the projectile itself, seldom exceeding three-fourths of the calibre and in no case reaching to 98 per cent of the calibre of the projectile so that the weight

of the cap forms about 7 or 8% of the total weight of the cap and projectile.

Now the present invention has for its object to produce a capped armor piercing projectile capable of being fired with the aid of existing range tables and of successfully penetrating modern hard faced armor of calibre thickness when striking the armor at a considerable obliquity, say of 20° or more to the normal, corresponding to long range and comparatively low velocity.

To attain this object we have found that it is necessary that the weight of the cap used should be equal to about 12% of the total weight of the combined cap and projectile, whilst the external contour of the cap should, as heretofore, be of seven calibres or more in radius, in order to obtain the required ballistic flight characteristics.

To produce a capped armor piercing projectile having the required weight of cap and external contour necessary for successful use as set forth, the armor piercing projectile is provided with an ogival shaped head of from one point five to one point seven calibre radius, preferably of about one point six calibre radius, the cap being arranged to extend over nearly the whole of the said head of the projectile and having an external contour formed mainly of two arcs of about seven calibres or more in radius struck from centres so situated that the arcs if extended rearward, would pass near to but outside the forward end of the body of the projectile. For this purpose the arcs may be struck from centres considerably in rear of the transverse plane of the bourelet. For the purpose of this invention, the longitudinal distance from the centres of these arcs to the transverse plane passing through the bourelet may be defined as being not less than three fourths of the calibre.

The construction above described permits of a cap being obtained of much greater weight, for a given overall length, than that which has heretofore been adopted with caps having an external contour of seven or more calibre radius, and of the diameter of the rear end of the cap being made of nearly the same diameter as the calibre of the projectile, say 98 per cent of the calibre, so that the weight of the cap may constitute 12% of the weight of the combined cap and projectile.

The solid cap is provided, as usual, with a hollow fore-cap the external contour of which corresponds with the external contour of the solid cap, so as to impart the required range and flight characteristics to the capped projectile. The forward end of the hollow fore-cap may be blunt as usual, and be of rounded or truncated conical shape, the forward ends of the arcs forming the external contour of the combined solid cap and hollow fore-cap terminating at the blunt forward end of the fore-cap.

In the accompanying illustrative drawings, Fig. 1 shows in central longitudinal section, a portion of a fourteen inch armor piercing projectile provided with a solid cap and hollow forecap embodying the invention, the head of the projectile having a radius of curvature of about one point six times the diameter of the body of the projectile. Fig. 2 is a sectional detail view showing a modification. Fig. 3 is a view in elevation illustrating a fourteen inch armor piercing projectile having incorporated therewith a cap embodying the features of my present invention and wherein the centres of the respective arcs are indicated diagrammatically.

As shown, the base end of the solid cap a extends back near to the bourelet b of the projectile and the front end e^1 of the hollow forecap e is made of truncated shape, the outline dimensions of the combined solid cap and hollow forecap being constituted by the two arcs f each of about seven calibres in radius. Each arc is struck from a centre considerably in rear of a transverse plane passing through the bourelet and so placed that the arc if extended rearwardly, would pass near to but outside the extreme forward end of the cylindrical surface of the body g of the projectile, the centres of the arcs being situated at a distance behind the said transverse plane not less than about three-fourths of the calibre of the projectile, as set forth. By the construction described the maximum diameter of the cap is, as will be seen, practically equal to the calibre of the projectile and the weight of the cap will be equal to about 12% of the total weight of the cap and projectile.

The truncated blunt front end e^1 of the hollow forecap e in the example, has a diameter of about one sixth or one seventh of the calibre of the projectile and may advantageously be made at its front surface of conical shape, advantageously of the obtuse angular shape shown, though it may, if desired, be made of rounded shape, as shown for example in Fig. 2, the front end of each case being therefore blunt.

The front end of the cap a is shown in the example as of rounded shape and having a radius of about eight inches from the

screw threaded junction i of the forecap e 65 with the cap a , towards the front end or tip a^1 of the cap where it may have a much smaller radius, say of about one point two four or two five inches.

In the exemplification of my invention as 70 illustrated in Fig. 3 k indicates the radius line defining the contour of the cap portion composed of the cap a and forecap e . In the fourteen inch projectile as illustrated this radius line k is of a length equal to 75 seven calibres of the projectile and the centre of this arc defining the curvature f of the combined main and fore-cap, as indicated diagrammatically at m , is located in the plane A A. This plane A A as noted occurs at a distance of 10.85", (.775 calibre), 80 behind the plane B B of the bourelet of the projectile. In similar diagrammatic manner the radius line defining the arc of curvature of the head of the projectile is shown 85 at n , said radius having a length as indicated of twenty-three inches and equal to 1.64 calibres of the projectile and the centre of the arc being indicated at o as occurring in the plane C C, the latter as illustrated being located a short distance behind the plane B B of the bourelet.

An armor piercing projectile fitted with a combined solid cap and a hollow forecap constructed as described, whilst of standard 95 overall dimensions and having standard ballistic and range characteristics, has a heavier cap and is better adapted for successfully penetrating thick hard faced armor plate at lower velocity and more obliquely 100 than the standard capped armor piercing projectile with hollow forecaps heretofore used.

What we claim is:—

1. An armor piercing projectile having an 105 ogival head of from 1.5 to 1.7 calibres radius and a solid cap extending nearly over the whole of the head of the projectile and having an external contour formed mainly of two arcs of about seven calibres or more 110 in radius struck from centres so situated that the arcs if produced rearward would pass near to but outside the forward end of the body of the projectile for the purpose set forth.

2. An armor piercing projectile provided with a combined solid cap and hollow forecap, the projectile having an ogival shaped head of from 1.5 to 1.7 calibre radius and the combined solid cap and fore-cap having an external contour formed mainly of two arcs of about seven calibres or more in radius struck from centers so situated that the arcs, if produced rearward, would pass near to but outside the forward end of the body 125 of the projectile, the solid cap extending backward over a large extent of the head of the projectile.

3. An armor piercing projectile provided with a combined solid cap and hollow fore-cap, the combined cap and fore-cap having an external contour formed mainly of two arcs of about seven calibres or more in radius struck from centers situated not less than three-fourths of the calibre of the projectile behind a transverse plane passing through the bourelet of the projectile so placed that the arcs, if produced rearward, would pass near to but outside the extreme forward extremity of the body of the projectile, the cap material extending backward over nearly the whole of the head of the projectile.

4. An armor piercing projectile having a pointed ogival shaped head of about 1.6 calibre radius, and a combined solid cap and hollow fore-cap having a blunt forward end, the external contour of the combined cap and fore-cap being formed mainly of two arcs of approximately seven calibres in radius struck from centers situated not less than three-fourths of the calibre of the projectile behind a transverse plane passing through the bourelet of the projectile and so placed that the arcs, if extended rearward, would extend near to but outside the forward end of the body of the projectile, the maximum diameter of the cap approximating to the calibre of the projectile, substantially as described for the purpose set forth.

5. A capped armor piercing projectile comprising a projectile having a pointed ogival shaped head of about 1.6 calibre radius, a solid cap fitting the head of the projectile and having a rear diameter approximating to the calibre of the projectile and a hollow fore-cap secured to the solid cap, the external contour of the combined solid cap and hollow fore-cap being formed of two arcs of about seven calibres or more in radius struck from centers so situated that the arcs, if extended rearward, would pass near to but outside the forward end of the body of the projectile for the purpose set forth.

6. A capped armor piercing projectile comprising a projectile having a pointed ogival shaped head of about 1.6 calibre radius, a solid cap fitting the head of the projectile and having a rounded front end surface, and a hollow fore-cap secured to the solid cap and having a blunt front end, the external contour of the combined solid cap and fore-cap being formed of two arcs of about seven calibres or more in radius struck from centers so situated that the arcs if extended rearward, would pass near to but outside the forward end of the body of the projectile, the solid cap material extending from in front of the point of the head of the projectile backward nearly over the whole extent of the said head and having a weight

of about 12% of the total weight of the capped projectile for the purposes set forth.

7. For an armor piercing projectile, of given calibre and weight, a cap having an external peripheral contour formed mainly of two arcs of not less than seven calibres radius struck from centers situated not less than three-fourths of the calibre behind the transverse plane of the bourelet of the said projectile, the maximum diameter of the cap being about ninety-eight percent of the calibre of the said projectile, and the ogival shaped cavity in the cap being of from 1.5 to 1.7 calibre radius the weight of the cap constituting about 12% of the total weight of the cap and its projectile for the purpose set forth.

8. For an armor piercing projectile of given calibre and weight, a cap having a rounded front end surface of smaller radius of the point or tip than at the remainder of such surface, and an external peripheral contour formed mainly of two arcs of not less than seven calibres radius struck from centers situated not less than three-fourths of the calibre behind the transverse plane of the bourelet of the said projectile, the maximum diameter of the cap being about ninety-eight percent of the calibre of the said projectile, and the ogival shaped cavity in the cap being of from 1.5 to 1.7 calibre radius, the weight of the cap constituting about 12% of the total weight of the cap and its projectile for the purpose set forth.

9. For an armor piercing projectile of given calibre and weight and having a pointed ogival shaped head of from 1.5 to 1.7 calibre radius, a combined solid cap and hollow fore-cap having an external contour formed mainly of two arcs of about seven calibres or more in radius struck from centers situated not less than three-fourths of the calibre of the projectile behind a transverse plane passing through the bourelet of the projectile, the maximum diameter of the cap being substantially equal to the calibre of the said projectile and the ogival shaped cavity in the said cap being of from 1.5 to 1.7 calibre radius the weight of the cap, the weight of the solid cap constituting about 12% of the total weight of the cap and projectile for the purpose set forth.

10. An armor piercing projectile having an ogival head defined by arcs of relatively small radii, and a solid cap extending over approximately the whole head of the projectile, the weight of the cap being approximately twelve per cent of that of the combined cap and projectile.

Signed at London, England, this tenth day of November 1919.
